HAND PRESS

Ferdinand Lindgren, Bridgeport, Conn., assignor
to Boering Specialty Co., Bridgeport, Conn., a
corporation of Connecticut

Application May 5, 1937, Serial No. 140,963

2 Claims. (Cl. 100—70)

This invention relates to improvements in hand presses.

In industry at the present time it is customary to perform a number of operations on small power presses and in kick presses. However, even the smallest of these are usually of considerable size and weight and take up considerable space. Also, because of their size and weight such presses are permanently secured to the floor or benches in the manufacturing establishment where they are being used.

It is a primary object of the present invention to provide a hand press which will be extremely small and light in weight so that it may be easily and quickly removed from the bench when it is no longer in use, and so that it may be easily and quickly moved from place to place in a factory.

A feature resulting from the attainment of this objective is the provision of a hand press, which although of very small size and weighing only a few pounds, is capable of creating pressure of two hundred and fifty pounds or more, with the expenditure of very little manual effort.

It is a further important object of the present invention to provide a hand press which may be easily manipulated from an inoperative to an operative position so that high quantity production may be obtained.

To this end, the present invention provides a hand press in which the operating lever is at all times at a convenient and accessible location whether it is in the operative or the inoperative position. Also, the invention provides spring means for normally urging the operating handle from the operative to the inoperative position thereby cutting down on the energy expended by the operator through the day to lift the handle to a raised inoperative position.

A further and important object of the present invention is the provision of a hand press which is operable over a wide range to perform satisfactorily on both short and long pieces of work.

In achieving this object the present invention provides the novel feature of a plunger or ram carrying block, having divers positions either close to a spaced or a considerable extent from the base of the hand press.

Other objects, features and advantages will appear hereinafter.

50 In the drawing:

Figure 1 is a front view of the hand press of the present invention.

Fig. 2 is a sectional view of the hand press shown in Fig. 1, taken on the line 2—2 of that figure.

Fig. 3 is a fragmentary view of a modified form of the present invention.

Before describing the present improvements and mode of operation thereof in detail it should be understood that the invention is not limited to the details of construction and arrangement of parts shown in the accompanying drawing, which is merely illustrative of the present preferred embodiments, since the invention is capable of other embodiments, and the phraseology employed is for the purpose of description and not of limitation.

Referring now in detail to the hand press of the present invention, and to Figures 1, 2 and 3 which illustrate the present preferred forms, there is provided a substantially L-shaped main frame 10 having a base 11 with a T-slot 12 and having an integral upright standard 13. Work may be placed directly upon the base 11 or work holding fixtures may be secured to the base as by bolts in the T-slot 12. Preferably the standard is provided with a slot 14 to divide the same into a pair of spaced vertical fingers 15. An integral and angularly disposed lug 16 is provided in back of the upright standard 13 in order to absorb the rearward strain imposed upon the standard 13 during normal operation of the hand press.

Now of particular importance the hand press of the present invention is provided with a slidable block 17 having a tongue 18 fitting into the slot 14 to be guided vertically thereby and having one or more bolts 19 extending through the slot for clamping the block 17 in any desired position relative to the base 11. The bolts 19 may be of one piece construction with integral head 20 and flange 21, or the latter may be in the form of a separate washer. Preferably two bolts 19 are provided to more rigidly secure the block to the standard. However, by using only the lower bolt it is possible to maintain the block in a position raised a considerable extent above the base, and with the upper bolt free and clear of the top of the standard 13.

In its preferred form the block is provided with a pair of horizontally disposed projections or fingers 22 and 23 extending forwardly over the base 11, preferably into a position overlying substantially the center of the base. A plunger or ram 24 is supported in the fingers 22 and 23 for reciprocatory movement toward and from the base 11. This ram may have an integral working head 25, to simply press down on certain pieces of work; or, it may be provided with an integral socket 26 adapted to receive a pointed, blunt or any one of a plurality of differently shaped and

differently functioning tools, which may be held therein by a screw 27.

The pair of horizontally disposed fingers are spaced sufficiently to provide a socket for a spring 30 and washer 31 which together with a pin 32 serve to retain the ram in a raised inoperative position relative to the base 11. Assembly thereof is effected by merely sliding the ram upwardly or downwardly through suitable bearings 33 in the fingers 22 and 23 and passing the same through the center of the spring and washer while they are disposed in a socket 34, formed between the fingers 22 and 23, and then passing the pin 32 through a suitable cross-drilled hole in the ram 24 when the parts are substantially in the position shown in Fig. 2. The pin 32 may be an ordinary cotter pin.

The fingers 22 and 23 are preferably provided with caps 22' and 23' held in place by screws 35, 20 to provide the bearings 33 for the ram 24 so that wear may be compensated for, and to always insure a snug sliding fit of the ram 24 in the block 17. If preferred, for economy and where the press is not to be put to hard use, the caps 22' 25 and 23' may be made integral with the fingers 22 and 23, and the bearings 33 provided by merely drilling, broaching, or otherwise machining the bearings 33 for the ram 24. A round ram may be provided; however, since it may be desirable 30 to provide a tool in the socket 26 which will remain in a fixed lateral relationship to work or fixture on the base the ram is preferably in the form of a square rod fitting into square bearings, such as the ram 24 and bearings 33 shown.

35 Thus, it will be seen that the spring 30 and pin 32 serve to retain the ram 24 in the block 17 for as the ram moves downwardly the pin compresses the spring. Passage of the ram upwardly out of the fingers 22 and 23 is prevented by the pin engaging the lower side of the finger 22 and passage downwardly and outwardly of the ram is prevented by the pin compressing the spring and washer toward the top of the lower finger 23.

The block 17 also includes an integral support 45 38 for an operating lever 39 and preferably including a handle 40. This support 38 is preferably in the form of a pair of forwardly projecting fingers 41 and 42 (see Figs. 1 and 2) with a socket 43 therebetween adapted to receive a flat 46 cam 44, preferably formed integral with the lever 39, with the cam pivotally mounted upon a stud 45 which passes through the forwardly projecting fingers 41 and 42 and is retained therein by pins 46. The cam 44 is proportioned and located to 55 overlie a head 47 on the ram 24 and thereby to work directly upon the ram. The handle 40 may be formed integral with the lever 39 but is preferably made of wood or other materials softer than the metal lever and is suitably secured on the lever 39 as by washers 48 and nut 49.

When the lever 39 is moved in a counter-clockwise direction, as viewed in Fig. 2, the cam 44 engages the top 47 of the ram 24 thereby compressing the spring 30 and forcing the ram 24 toward the base 11 to cooperate with work on the base. Movement of the ram 24 to the raised and inoperative position is effected by merely moving the lever 39 into the raised position. The 70 spring 30 and ram 24 working upwardly against the cam 44 facilitates return of the lever to the raised and inoperative position.

A larger or smaller base 11 may be provided

on the fixture, as desired. It has been found in practice and use that the fixture remains on a bench in quite a satisfactory manner without the use of any fastening elements. However, when the fixture is intended to remain on a bench for 5 a long time it is preferable to secure it to the bench. For this purpose the present invention provides a threaded hole 54 at the underside of the base 11 to which any suitable fastening bolt passed through the bench 55 may be secured. As 10 shown, this is accomplished by a headless bolt 56 tightened into the threaded hole 54 and passed through a hole 57 in the bench where it is rigidly secured by a knob nut 58 as shown in Fig. 2.

The block 17 may be made integral with the 15 standard 13. However, the one hand press is adaptable for a wider range of work through the provision of the various ram locations made possible with the loose or slideable block 17, which may be locked in various positions relative to 20 the base 11.

If preferred, projecting fingers 41' and 42' may, as shown in Fig. 3, be provided to extend sideways in the block 17', so that the lever 39 will extend toward the side of the hand press rather than forwardly from the press. The only real point of difference in this structure over that form disclosed in Figs. 1 and 2 is the provision of a single forwardly projecting finger 60 supporting the pair of fingers 41' and 42' which projects toward the side of a machine rather than toward the front as do the fingers 41 and 42.

Variations and modifications may be made within the scope of this invention and portions of the improvements may be used without others. 35

Having thus described the invention, what is claimed as new is:

1. In a hand press the combination of a one-piece main frame having a base; a bifurcated standard thereon; a block slidably mounted on the standard having a tongue projecting between the legs of the standard in guiding engagement; a pair of spaced bolts threaded into the block and engaging the opposite side of the standard for holding the block securely in any desired 45 position on the standard; spaced lugs made integral with the upper portion of the block; a cam member journaled in said lugs; spaced apertured arms integral with the block below the lugs; and a ram reciprocally mounted in the arms in position to be acted on by the cam member and its lower end being above said base; said tongue extending throughout the length of the block from above the cam member to below the lowermost one of the arms. 55

2. In a hand press the combination of a one-piece main frame having a base; a bifurcated standard thereon; a block slidably mounted on the standard having a tongue projecting between the legs of the standard in guiding engagement; a pair of spaced bolts threaded into the block and engaging the opposite side of the standard for holding the block securely in any desired position on the standard; spaced lugs made integral with the upper portion of the block; a cam member journaled in said lugs; spaced apertured arms integral with the block below the lugs; and a ram reciprocally mounted in the arms in position to be acted on by the cam member and its lower end being above said base; said tongue having 70 portions extending for a substantial distance lengthwise of the block. 65
